UNITED STATES PATENT OFFICE.

JACOB J. WERNER, OF HEBRON, NEBRASKA.

DESIGN FOR A CLAMPING-BAND FOR STOVEPIPE-ELBOWS.

SPECIFICATION forming part of Design No. 31,199, dated July 11, 1899.

Application filed June 13, 1899. Serial No. 720,411. Term of patent 14 years.

To all whom it may concern:

Be it known that I, JACOB J. WERNER, of Hebron, in the county of Thayer and State of Nebraska, have invented and produced a new and original Design for a Clamping-Band for Stovepipe-Elbows, of which the following is a full, clear, and exact specification.

Reference is to be had to the accompanying drawings, forming a part of this specification, in which similar characters of reference indicate corresponding parts in all the figures.

Figure 1 is a plan view of a clamping-band for stovepipe-elbows, showing my design. Fig. 2 is a side elevation of the same, and Fig. 3 is a front elevation of the same with part in section.

The design in its entirety consists of the

open-ended band A, approximately circular in shape, the ends being turned outward and backward to form hooks B, the middle portion A' of the band being somewhat reduced in width and the upper edge along the reduced portion formed into a bead C and the lower end D being beveled inward, as shown.

The leading feature of the design consists of a band having a partial bead at one edge.

I claim—

The design for a clamping-band for stovepipe-elbows herein shown and described.

JACOB J. WERNER.
